Des. 186,400
Patented Oct. 20, 1959

186,400

ELECTRIC LIGHT FIXTURE

Kenneth E. Belau, Milwaukee, Wis., assignor to Spincraft,
Inc., Milwaukee, Wis., a corporation of Wisconsin

Application May 16, 1958, Serial No. 50,928

Term of patent 14 years

(Cl. D48—23)

Fig. 1.

Fig. 2.

Fig.3.

Fig.4.

Figure 1 is a top perspective view of an electric light fixture embodying my new design;

Figure 2 is a side elevational view thereof;

Figure 3 is a bottom perspective view of the electric light fixture; and

Figure 4 is a sectional view taken through the center thereof including the light elements.

The dominant features of my design reside in those portions thereof shown in full lines.

I claim:

The ornamental design for an electric light fixture, as shown and described.
